UNITED STATES PATENT OFFICE.

FERNAN O. CONILL, OF PORT JEFFERSON, NEW YORK.

GUN.

1,405,291.

Specification of Letters Patent. Patented Jan. 31, 1922.

Application filed August 7, 1918. Serial No. 248,793.

To all whom it may concern:

Be it known that I, FERNAN O. CONILL, a citizen of the Republic of Cuba, residing at Port Jefferson, Long Island, in the county of 5 Suffolk and State of New York, have invented certain new and useful Improvements in Guns; and I do hereby declare the following to be a full, clear, and exact description of the invention, such as will enable 10 others skilled in the art to which it appertains to make and use the same.

This invention relates to guns, and more particularly to a gun which is especially adapted for firing projectiles provided with 15 explosive charges for propelling the same from the gun.

One of the main objects of the invention is to provide a gun of the character stated of simple construction and operation by 20 means of which a projectile may be slid down the barrel of the gun from the muzzle end thereof, this projectile being provided with an explosive charge which is exploded through the medium of means provided 25 within the gun.

A further object is to provide a gun having means whereby a projectile to be shot therefrom may be supported within the muzzle end of the barrel of the gun so as to 30 be readily released, when desired.

Further objects will appear from the detailed description.

The single figure of the drawing is a longitudinal sectional view through a gun constructed in accordance with my invention, as used.

The gun comprises a body 1 which is provided at its base portion with diametrically opposite horizontally projecting trunnions 40 2 rockably mounted in bearing sleeves 3 formed at the upper ends of spaced supporting standards 4 carried by a base plate 5 which is adapted to be secured on a suitable foundation or supporting structure 6. This 45 body comprises a barrel 1^a provided with an interior bore of substantially uniform diameter throughout its full length, this bore communicating with a frusto-spherical explosion chamber 7 formed in the rounded 50 base 8 of the gun. The barrel 1^a is provided with a thickened annular portion 1^b from which depends an integral relatively heavy lug 9 provided at its lower end with an integral eye 10 which receives a pivot pin 11 55 inserted therethrough and through the spaced arms of a U-member 12 snugly re-

ceiving this eye. The base bar 12^a of this U-member is connected by a loose nut connection, as at 13, to a screw rod 14 threaded through a sleeve 15 which is pivotally secured for movement about an axis parallel with the axis of pin 11, as at 16, to the upper end of a standard 17 projecting from base plate 5. The rod 14 may be rotated in either direction by means of a hand wheel 18 secured thereon so as to readily vary the inclination of the barrel 1^a. As the U-member 12 and the sleeve 15 are mounted for movement about parallel axes, these members will at all times be maintained in proper alinement so that all pressure which may be exerted on the screw 14 will be transmitted axially thereof thus eliminating possibility of bending or breakage of this member.

This gun is specially adapted for use in connection with a shell or projectile which carries the explosive charge for propelling the same from the gun. In the form illustrated, the projectile designated generally by 80 P comprises a body portion *a* from the base of which depend concentric annular flanges *b* and *c* forming an annular chamber for the reception of an explosive charge *D*, and an inner tubular chamber at the inner end 85 of which is mounted a percussion cap *e* which communicate with the chamber containing the explosive charge *d* by means of ducts *f* formed through the flange *c*.

After the gun has been properly set and 90 sighted, the projectile is inserted into the muzzle end 1^c of the barrel 1^a and permitted to slide downwardly therein. As the projectile approaches the lower or base end of the gun, the cap *e* is brought into contact 95 with the upper pointed end of a firing pin 19 which projects upwardly into the barrel 1^a, centrally thereof, from a boss 20 formed on the inner face of base 8. This serves to explode the charge *d*, the explosion taking 100 place in the explosion chamber 7, which results in propelling the projectile from the gun in the well known manner. This eliminates all necessity of providing the usual firing mechanism such as employed in guns 105 now in common use, while permitting the gun to be fired very rapidly. By providing means whereby the projectiles may be supplied to the upper or muzzle end of the gun in quick succession, a relatively great number 110 of these projectiles may be fired from the gun in a comparatively short time.

To permit the projectile to be lowered into firing position, at will, I provide a stop member which projects into the bore of the barrel so as to engage a projectile inserted therewith and hold it against downward movement, this member being readily movable out of the path of the projectile so as to permit the same to slide into firing position. With this object in view, a bell crank lever 21 is pivotally mounted intermediate the ends of the longer arm 22 thereof, as at 23, on a supporting finger 24 projecting from the barrel 1^a. The shorter arm 25 of this lever projects through an opening 26 in the barrel into the bore thereof, the lower end of the longer arm 22 being normally forced away from the barrel by an expansion coil spring 27 seated in a nipple 28 formed on the under face of the barrel and confined between arm 22 and this nipple. When the lever 21 is in its normal position, arm 25 projects into the bore of the gun and serves as a stop member for positively limiting downward movement of a projectile inserted into the muzzle end 1^c of the barrel, as indicated by dotted lines. When it is desired to release the projectile, the lever may be rocked outwardly by means of a cable or lanyard 27', the end of which is secured through an eye 28' formed at the angle of the lever. By rocking the lever outwardly, shorter arm 25

thereof is moved out of the path of the projectile which slides downwardly into firing position, so as to cause explosion of the explosive charge D carried thereby in the manner previously described. 35

It will be evident that there may be slight changes made in the construction and arrangement of the details of my invention without departing from the field and scope 40 of the same, and I intend to include all such variations, as fall within the appended claims, in this application in which a preferred form only of my invention is disclosed. 45

What I claim is:

1. In a firing mechanism, a base having spaced standards, a gun pivoted at its breach to one of the standards, a screw rod rotatably mounted upon the gun, and a nut for the rod pivoted to the other standard. 50
2. A gun pivoted adjacent its breech, a screw rod having a head, a mounting member pivoted to the gun and rotatably receiving the head, means to turn the screw rod, 55 a nut on the rod, and means to pivotally mount the nut.

In testimony whereof I affix my signature.
FERNAN O. CONILL.
